PORTABLE CONCRETE RODDING MACHINE

Marvin E. Whiteman, Los Angeles, Calif.

Application October 31, 1941, Serial No. 417,285

11 Claims.

This invention relates to a portable concrete rodding or screeding machine.

A primary object of the invention is to provide a portable concrete rodding or screeding machine that may be advantageously utilized in the construction of concrete floors, concrete slabs and the like. Heretofore it has been customary practice in the construction of a concrete floor to temporarily mount at the side boundaries of the concrete that is to be poured guide strips or grounds, the top surfaces of which are arranged at the desired level to which the concrete is to be poured. Then a rod or screed is worked back and forth transversely with respect to the grounds to strike off the excess concrete and to render the concrete level with the top surface of the grounds. The reciprocation of the rod also tends to work the cement and fine aggregate toward the surface, after which the concrete may be surfaced manually or by machine, or if desired, a finish coat of cement may be applied thereover.

The present invention contemplates a machine for accomplishing the above-mentioned purpose wherein the machine is adequately heavy to work and strike off an adequate area of poured concrete but will also be adjustably and yieldably supported so that the entire weight of the machine does not rest on the grounds or guide strips. In this manner the machine operates with a minimum amount of friction and danger of disturbing the grounds is largely eliminated.

Another object of the invention is to provide a portable concrete rodding or screeding machine which is of relatively simple and durable construction and which is readily portable from job to job.

Another object of the invention is to provide a portable concrete rodding or screeding machine employing transversely movable screeds so arranged that movements of the screeds are transverse and opposite so that vibratory tendencies created by the movements of the screeds are largely neutralized whereby the machine is caused to operate smoothly and efficiently.

With the foregoing and other objects in view, which will be made manifest in the following detailed description and specifically pointed out in the appended claims, reference is had to the accompanying drawings for an illustrative embodiment of the invention, wherein:

Figure 1 is a top plan view of a concrete floor illustrating grounds or guide strips as having been set, and illustrating the rodding or screed-

(CH 24 145)

ing machine embodying the present invention in operative position thereon;

Fig. 2 is a front view in elevation of the portable concrete rodding or screeding machine;

Fig. 3 is a vertical section taken substantially upon the line 3-3 upon Fig. 1 in the direction indicated;

Fig. 4 is a vertical section taken substantially upon the line 4-4 upon Fig. 1 in the direction indicated;

Fig. 5 is a vertical section taken substantially upon the line 5—5 upon Fig. 1 in the direction indicated; and

Fig. 6 is a horizontal section taken substantially upon the line 6—6 upon Fig. 4 in the direction indicated.

Referring to the accompanying drawings wherein similar reference characters designate similar parts throughout, 10 and 11 indicate grounds or guide strips that are usually mounted temporarily at the sides of an area of floor space that is to be poured with concrete C. The improved portable concrete rodding machine comprises a transversely extending plate or frame 12 on which is preferably mounted a gear box 13 driven by any suitable source of power, such as an electric motor 14. A belt or chain 15 may connect the motor 14 with the gear box.

connect the motor 14 with the gear 15.

The gear box has on its underside an eccentric 16 the eccentric pin of which is connected by a connecting rod 17 to a pivot 18. A handle 19 extends upwardly and forwardly from the gear box and may be equipped with an electric switch 20 controlling the electric current delivered through conductors 21 to the electric motor 14. On the under side of the frame 12 adjacent opposite ends thereof there are cross bars 22 and 23, these being pivotally mounted adjacent their centers on pivot studs 24. The rear ends of the cross bars 22 and 23 are pivotally connected at 25 and 26 to transversely extending angle irons 27. A screed or rod 28 preferably formed of wood is detachably mounted upon the angle irons 27 such as by bolts 29. In a similar manner, the forward ends of the cross bars 22 and 23 are pivotally connected by means of the pivot pin 18 and a pivot 30 to angle irons 31 on which a forward screed 32 is detachably mounted as by bolts 33. The screeds 28 and 32 are slightly greater in length than the distance between the ground and the guide strips 10 and 11, and are thus mounted for transverse back and forth movement relatively to the frame as indicated by dotted lines on Fig. 1.

Adjacent each end of the frame there is hingedly mounted as by hinges 34 supporting arms 35 which provide trunnions or axles for supporting wheels or discs 36. The arms 35 are yieldably urged downwardly against the top of the frame by means of coil compression springs 37 disposed about bolts 38 having adjustable nuts 39. The discs or supporting wheels 36, together with their associated structure, serve to yieldably support the major portion of the weight of the machine so that, although the bottom surfaces of the screeds or rods 28 and 32 rest and rub on the top surfaces of the grounds 10 and 11, the entire weight of the machine is not caused to rest on the grounds but is largely carried by the supporting 15 wheels or discs 36.

The operation and advantages of the improved portable rodding or screeding machine are as follows: When the concrete is poured between the forms 10 and 11, the machine is started up by closing switch 20. This causes the motor 14 to drive the eccentric 16 through the gear box 13 with the result that the connecting rod causes the forward screed 32 to move back and forth in a transverse direction. The cross bars 22 act as simple levers causing the rear screed 28 to move back and forth transversely in a similar manner. The movements of the two screeds are however simultaneous and opposed. That is, while the forward screed is moving toward the right the rear screed is forced to move toward the left and when the forward screed is moving toward the left, the rear screed is forced to move toward the right. The machine is slowly pulled forwardly in a longitudinal direction by the handle 19 while the reciprocatory movement of the screeds is taking place.

The forward screed serves largely to strike off or to level out the excess concrete as indicated in Fig. 3 and the rear screed performs largely a finish screeding or rodding operation filling the narrow grooves that may be left by the thin supporting wheels or discs 36. The extent to which the supporting wheels or discs 36 support the weight of the machine may be varied or adjusted by means of nuts 39 and adjustment of these nuts may be required whenever the depth to which the concrete is poured is varied.

While it is possible to construct a machine having merely one screed, the use of two screeds is highly preferable in that the opposed motions of the screeds tend to neutralize each other insofar as vibration of the machine is concerned. Consequently the machine may be found to operate quite smoothly and efficiently in striking off and levelling the poured concrete. In the course of use the screeds 28 and 32 become worn in which event they can be readily removed and replaced.

From the above-described construction it will be appreciated that the improved machine is capable of performing adequately the rodding and screeding operations that have heretofore been performed by hand. Although the machine has the necessary weight to strike off a relatively large area of excess concrete, the entire weight of the machine is not supported on the grounds or guide strips 10 and 11. Only sufficient weight is allowed to rest on these grounds to effectively strike off the concrete to the desired level. Thus, danger of disturbing the grounds is eliminated and the concrete is levelled to the level determined by the temporarily mounted grounds.

Various changes may be made in the details of construction without departing from the spirit or

scope of the invention as defined by the appended claims.

I claim:

5 1. A portable concrete rodding machine comprising a transversely extending frame, means for moving the frame longitudinally, cross bars pivotally mounted upon the frame, transversely extending screeds pivotally connected to the cross bars, one of said screeds being disposed forwardly of the frame and the other rearwardly thereof, motor driven means on the frame for reciprocating the screeds, and means on the frame between the screeds engageable with the bed of concrete that is to be rodded to resist lateral movements of the machine.

2. A portable concrete rodding machine comprising a transversely extending frame, means for moving the frame longitudinally, cross bars pivotally mounted upon the frame, transversely extending screeds pivotally connected to the cross bars, one of said screeds being disposed forwardly of the frame and the other rearwardly thereof whereby the weight of the machine will tend to settle to that level limited by the engagement of the screeds with guide strips, and motor driven means on the frame for reciprocating one of the screeds causing the other to be simultaneously reciprocated but in the opposite direction.

3. A portable concrete rodding machine comprising a transversely extending frame, means for moving the frame longitudinally, cross bars pivotally mounted upon the frame, transversely extending screeds pivotally connected to the cross bars, one of said screeds being disposed forwardly of the frame and the other rearwardly thereof whereby the weight of the machine will tend to settle to that level limited by the engagement of the screeds with guide strips, motor driven means on the frame for reciprocating the screeds, and means assisting in supporting the frame located between the screeds.

4. A portable concrete rodding machine comprising a transversely extending frame, means for moving the frame longitudinally, cross bars pivotally mounted upon the frame, transversely extending screeds pivotally connected to the cross bars, one of said screeds being disposed forwardly of the frame and the other rearwardly thereof whereby the weight of the machine will tend to settle to that level limited by the engagement of the screeds with guide strips, motor driven means on the frame for reciprocating one of the screeds causing the other to be simultaneously reciprocated but in the opposite direction, and wheels yieldably mounted upon the frame for assisting in supporting the frame for longitudinal movement.

5. A portable concrete rodding machine comprising a transversely extending frame, means for moving the frame longitudinally, cross bars pivotally mounted upon the frame, transversely extending screeds pivotally connected to the cross bars, one of said screeds being disposed forwardly of the frame and the other rearwardly thereof whereby the weight of the machine will tend to settle to that level limited by the engagement of the screeds with guide strips, motor driven means on the frame for reciprocating one of the screeds causing the other to be simultaneously reciprocated but in the opposite direction, and a wheel at each end of the frame the axis of rotation of which is in the same vertical plane as the pivots for the cross bars.

6. A portable concrete rodding machine com-

prising a frame, a handle on the frame by which it may be moved longitudinally, arms hingedly mounted upon the frame adjacent the ends thereof, wheels on the arms, spring means yieldably supporting the frame upon the arms, one or more transversely extending screeds mounted for transverse reciprocation on the frame, and power driven means for transversely reciprocating the screeds.

7. A portable concrete rodding machine comprising a transversely extending frame, means for moving the frame longitudinally, wheels adjacent the ends of the frame arranged so that the frame will be substantially balanced thereon, transversely extending screeds at the front and back of the frame substantially equi-distant from the axis of rotation of the wheels, said wheels constituting the sole means of support of the frame except for the supporting effect of the screeds, and motor driven means for reciprocating the screeds.

8. A portable concrete rodding machine comprising a transversely extending frame, means for moving the frame longitudinally, wheels adjacent the ends of the frame engageable with the concrete bed to resist lateral movements of the machine and arranged so that the frame will be substantially balanced thereon, transversely extending screeds at the front and back of the frame substantially equi-distant from the axis of rotation of the wheels, said wheels constituting the sole support for the frame except for the supporting effect of the screeds, and motor driven means for reciprocating the screeds simultaneously and in opposite directions.

9. A portable concrete rodding machine comprising a transversely extending frame, a handle on the frame for moving the frame longitudinally, wheels adjacent the ends of the frame arranged so that the frame will be substantially balanced

thereon, said wheels being engageable with the bed of concrete that is to be rodded to resist lateral movements of the machine, transversely extending screeds at the front and back of the frame substantially equi-distant from the axis of rotation of the wheels, and motor driven means for reciprocating the screeds, said wheels being yieldably mounted upon the frame so as to only partially carry the load of the frame enabling the balance of the weight of the frame to press the screeds against guide strips.

10. A portable concrete rodding machine comprising a transversely extending frame, a handle on the frame for moving the frame longitudinally, wheels adjacent the ends of the frame arranged so that the frame will be substantially balanced thereon, transversely extending screeds at the front and back of the frame substantially equi-distant from the axis of rotation of the wheels, levers pivotally mounted centrally upon the frame and pivotally connected to the screeds, and motor driven means on the frame for reciprocating one of the screeds causing both screeds to be reciprocated simultaneously and in opposite directions.

11. A portable concrete rodding machine comprising a transversely extending frame, a handle on the frame for moving the frame longitudinally, transversely extending screeds at the front and back of the frame, motor driven means for reciprocating the screeds, and means for yieldably supporting the frame between the screeds whereby the frame and screeds may tend to be balanced about the supporting means and a portion of the weight of the machine will be carried by the supporting means and the balance employed to press the screeds against guide strips.
